FRUIT SHIPPING CARTON

Willis F. Luce, San Francisco, Calif.

Application June 6, 1932. Serial No. 615,533

3 Claims. (Cl. 229—14)

This invention relates to cardboard, fiber board, and like cartons, and especially to a carton of this character which is intended for the transportation or shipment of fruit.

It has been common practice for many years to pack and ship such fruits as cherries, apples, oranges, lemons, et cetera in wooden boxes. The usual type of box consists of rigid end sections and comparatively rigid side and bottom sections, on top of which is placed a fairly flexible or bendable cover section. In packing fruits in boxes of this character, the uppermost layer of fruit projects slightly above the upper edges of the box and when the flexible cover sections, which consist of slats or shooks, are nailed in place they are bent or sprung and assume a considerable curvature. During shipment, the fruit tends to shrink and settle in the box and the spring in the shooks or slats takes up the shrinkage, thus retaining the fruit in a tightly packed position and avoiding shifting of the fruit and bruising by bumping one against the other.

During the last few years, at least here in the West, a number of attempts have been made to ship fruits in cardboard or fiber board cartons, but such materials do not have the resiliency of board shooks or slats and there is no means for compensating for the shrinkage of the fruit during shipping. The fruit, accordingly, becomes loose in the cartons and shifts about and is often damaged by the time it reaches its destination. Cartons also present a problem when shipped in standard refrigerator cars, as the railway regulations require that fruit, when shipped in boxes or cartons, must be stacked in spaced tiers to insure proper circulation of cool air during shipment and they also require proper bracing to prevent damage by shifting. Such bracing can only be applied by nailing cross slats, et cetera, to the boxes and as cardboard cartons will not hold the nails proper bracing has presented a difficult problem.

The object of the present invention is to generally improve and simplify the construction and operation of cardboard, fiber board cartons, or the like; to provide a carton having means for taking up shrinkage of fruit during transportation; to provide a carton which may be stacked in tier formation without subjecting the fruit in the lowermost cartons to the superposed weight of the cartons placed above the same; and further, to provide a carton having a wood insert to receive and retain the nails for bracing purposes during shipment.

55 A carton embodying the above features is shown

by way of illustration in the accompanying drawings, in which—

Fig. 1 is a longitudinal vertical section of a cardboard carton showing the same filled with fruit and the spring board applied. 60

Fig. 2 is a cross section taken on line II—II of Fig. 1.

Fig. 3 is a perspective view of the spring board.

Fig. 4 is a section similar to Fig. 1, showing a modified form of the wooden insert. 65

Fig. 5 is a diagrammatic view showing the manner in which the cartons are stacked.

Fig. 6 is a partial cross section of a refrigerator car, showing the manner of stacking and cross bracing the cartons. 70

Referring to the drawings in detail, and particularly Figs. 1 to 3, A indicates the bottom, 2 the ends, 3 the sides, and 4 the top or cover member of a carton. The carton is suitably constructed of cardboard, fiber board, or a similar material and, in this instance, is intended for use in the shipment or transportation of fruits and other commodities. 75

As heretofore stated, an ordinary paper or cardboard carton is not suitable for the transportation of fruit, the main reasons being that means are lacking for taking up shrinkage of the fruit during transportation and that paper cartons do not hold or retain nails driven into them and as such are not suitable where bracing is required. These difficulties are overcome in the present instance by providing a wooden insert comprising a pair of comparatively heavy wooden cross cleats 6 to which are nailed, or otherwise secured, a thin wooden panel 7 which is sufficiently flexible to function as a spring board; that is, to bend and yield when inserted and to take up shrinkage during transportation. The panel may be made in one section, as shown in Fig. 3, or it may be made from a number of slats, as indicated by dotted lines at 7a, and the slats may be nailed or otherwise secured to the cleats 6. 85

The insertion of a spring board, such as described, will accordingly solve the problem of shrinkage of the fruit. It also solves the bracing problem as the comparatively heavy end cleats 6 permit nails to be driven through the bracing slats into the cleats and as these are made of wood the nails will be rigidly secured and retained in order that no pressure shall be applied to damage the fruit when the bracing is being nailed to the cartons. A pair of comparatively heavy corrugated boards 8 are inserted in each end of the carton. These boards 100

105

110

are inserted before the carton is filled with fruit and as such are held in a vertical position when the fruit is placed in the box. The spring board is then placed on top of the fruit and the end sections 8 are supported thereby, the spring board yielding and curving upwardly, as shown in Fig. 1 to accommodate the fruit. The cover is then applied and secured in any suitable manner and the carton is ready for shipping.

10 During shipping, especially in refrigerator cars, the cartons are stacked, as shown in Fig. 6. That is, they are placed on top of each other in rows or tiers and cross cleats 9 are placed crosswise of the cartons between the side walls 15 of the refrigerator car. The slats are nailed to the cartons by driving the nails through the slats in the cover of the carton and into the cleats 6, and the cartons are thus rigidly braced and spaced apart, as indicated at 10, to permit 20 circulation of the cold air from the icebox. The cross cleats, together with the corrugated end sections 8, serve still another function, to-wit, that of carrying the weight of superposed cartons, see Fig. 5. Where a number of cartons 25 are placed on top of each other, the bottom sections A of the respective cartons tend to bulge slightly due to the weight of the fruit. Such bulging is permitted when cartons of this character are employed as it will merely cause 30 a slight yielding of the cover section of each carton. The weight of the fruit in the superposed carton will, however, be supported by the cross cleats and the end sections 8 and the fruit in each carton will merely be subjected to its 35 own weight and not to the weight of the superposed cartons. Hence, it is possible to stack the cartons in higher tiers than has heretofore been possible without damage to the fruit and a greater load may be handled in the refrigerator 40 cars.

Where other commodities are being transported in cardboard cartons, particularly where shrinkage does not form a major problem, a modified wooden insert may be employed, as shown in Fig. 45 4, that is, the cardboard carton is constructed in

the usual manner, but before the carton is packed, corrugated iron sections 11-11 are inserted. These are bent at right angles at their upper ends, as indicated at 11a, and to each is nailed or otherwise secured a cross cleat 12. These cleats, together with the end sections 11, function to carry the load of superposed cartons and they also function as nail holding means where bracing is required. Hence, the wooden inserts may take either the form shown in Fig. 1 where shrinkage is encountered, or the form shown in Fig. 4 where the spring board may be eliminated.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. In combination with a cardboard carton adapted to contain a shrinkable commodity, a flexible panel within the carton in contact with the commodity, and means insertable between each end of the panel and a cover on the carton to spring the panel and maintain it under tension.

2. In combination with a cardboard carton adapted to contain a shrinkable commodity, a flexible panel within the carton in contact with the commodity, and a cleat interposed between each end of the panel and a cover on the carton to spring the panel and maintain it under tension.

3. In combination with a cardboard carton adapted to contain a shrinkable commodity, a flexible panel within the carton in contact with the commodity, means insertable between each end of the panel and a cover on the carton to spring the panel and maintain it under tension, and a supporting member insertable in each end of the carton and interposed between the ends of the panel and the bottom of the carton.
